DIAPHRAGM CLOSURE FOR PASTE SHOE
POLISH CONTAINER EQUIPPED WITH A
DAUBER

Howard L. Auten, East Peoria, Ill.

Application June 17, 1950, Serial No. 168,764

3 Claims. (Cl. 15—140.4)

1

This invention relates to a polisher. The invention is particularly useful in connection with a container for paste or shoe polish.

An object of the invention is to provide a structure in which the dauber or applicator is supported within a diaphragm closure which permits movement of the dauber into a plurality of vertical positions. A further object is to provide a structure in which the dauber is fitted within an arched shape closure, permitting clearance for it above the contents of the container when the closure is on the container. A still further object is to provide a closure provided with a flexible top in which is secured a dauber and permitting the movement of the dauber to elevated and depending positions. A still further object is to provide a metal or rigid rim structure around the outside of the closure for supporting and reinforcing a flexible diaphragm in which the applicator is secured. Yet another object is to provide a closure equipped with a diaphragm to which an applicator is secured on the inside and a handle extends on the outside of the diaphragm, whereby, through pressure upon the handles, the applicator may be moved into a position above the contents of the container when the closure is in position and to depending position when the closure is removed. Yet another object is to provide a polisher in which an applicator and polishing means are supported as a unitary portion of the container, the top surface of the closure being extended upwardly to provide a handle and the bottom surface of the container being equipped with polishing means. Yet another object is to provide a diaphragm-equipped closure adapted for use with a polish container wherein a diaphragm in arched position is employed for supporting a dauber above the polish when the closure is in position, while permitting the dauber to be moved to a depending position well below the diaphragm when the closure is removed. Other specific objects and advantages will appear as the specification proceeds.

The invention is shown in an illustrated embodiment, by the accompanying drawing, in which—

Fig. 1 is a perspective view of a polisher embodying my invention; Fig. 2, a vertical sectional view; Fig. 3, a sectional view of the closure in removed position and with the dauber occupying a depending position; Fig. 4, a bottom plan view of the closure removed from the container; and Fig. 5, a broken sectional view showing a modified form of the invention.

2

In the structure shown, 10 designates a container which may be filled with polish 11. The container 10 may be pressed inwardly to provide a peripheral groove 12, as shown best in Fig. 2. A plate 13 provided with a polishing surface 14 may be anchored to the bottom portion of the container 10 through the use of a spring flange or spring fingers 15 entering the recess 12 and being secured therein by a snap ring 15a. The plate 13 may be slotted at intervals so as to give the flanges or spring fingers 15 greater elasticity and tenacity in engaging the locking recess 12. The polishing surface 14 may consist of sheepskin with the leather side bonded to the metal plate or of any other suitable polishing material secured to the plate. If desired, the sheepskin or other polisher device may be employed without a plate and the leather or fabric portion 13 secured directly by the snap ring 15a.

20 The container may be provided with a loosener bar 16 pivotally-mounted upon the pin 17.

The closure 18 may be formed of any suitable material and in any suitable shape. In the illustration given, I provide an arched closure which 25 in effect provides a diaphragm. The diaphragm or closure 18 may be formed of metal, plastic or any other resilient type of material. Polyethylene plastic has been found very satisfactory and heavy cellophane, chlorinated rubber, rubber and synthetic rubber, and a large variety of materials 30 may be used.

In the specific illustration given, I have shown a plastic closure 18 provided with a molded annular rim 19 on the exterior of the closure and a molded annular rim 20 on the lower portion of the closure. An applicator consisting of a brush holder 21 and bristles 22 extending from the holder is secured tightly within the annular rim 20 on the underside of the closure, while a handle 23 tightly fits within the annular rim 19 on the upper side of the closure. A screw 24 secures the applicator and handle together. Instead of the screw, cement or other means may be employed.

45 In the illustration given, the closure member or diaphragm member 18 is provided with a metal ring 25 which provides a reinforcement for the lower edge of the closure and is found to be very effective in bringing about a tight seal with the container 10. It will be understood, however, that the ring 25 may be omitted if desired. The closure or diaphragm 18, however, is formed of certain materials which do not form a tight seal with the container. The ring 25 is very effective 50 in providing the desired tight seal and serves to 55

prevent escape of volatile vapors from the polish material within the container.

The metal rim or ring may be riveted to the closure 18 or crimped over, as illustrated in Fig. 5, in which the metal rim is indicated by the numeral 25a.

Operation

In the operation of the structure, the closure 18 is effective normally in maintaining the brush 22 in an elevated position and above the level of the polish 11 in the container by reason of the arched shape or diaphragm-like structure of the closure. At the same time, if the operator desires to apply polish upon the brush, he may depress the diaphragm 18 slightly to bring the brush into engagement with the polish. After the removal of the cover, the rim of the closure may be held in one hand and lateral or downward pressure applied to the handle, making the diaphragm collapse, as illustrated in Fig. 3. Further downward pressure causes the diaphragm 18 to swing to the depending position shown in Fig. 3. In the latter position, the brush is suspended well below the diaphragm and the polish may be thus readily applied to the shoes. It will be noted that the downward swinging of the diaphragm further protects the hands from contact with the brush and with the surfaces of the shoes to which fresh polish has been applied. In effect, there is a raising of the rim or periphery of the closure so that it is out of the way of the shoes or objects to which the polish is applied, while at the same time the rim occupies a more sheltering position around the fingers which grasp the handle 23.

After the applicator has been moved to its depending position, as illustrated in Fig. 3, it is then ready for use and, by holding the closure by the handle or closure rim, a quantity of paste may be picked up in the brush applicator and the user can apply the brush over the shoes with great speed.

After the polish has been applied to the shoes, the closure may be restored to its original position by tilting the handle to the intermediate position illustrated in Fig. 3 and then upward pressure on the lower side of the closure handle causes the closure to spring back to its original shape. The closure may be placed upon the container and sealed in the usual manner.

The bottom of the container, which is now supported by the handle, may be employed as a polisher for the shoes to which the paste or polish has been applied.

If desired, the applicator-equipped closure may be used with a variety of cans or polish. The ordinary cover for the can may be discarded and the closure 18 substituted. Thus the applicator and its closure may be effectively used for a long period of time.

With the foregoing type of structure, it is found that polish can be readily and accurately applied without bringing the fingers into contact with any polish particles, the diaphragm serving not only as a means for maintaining the brush above the top surface of the polish but also, when the closure is removed, projecting the brush downwardly to a point where it is considerably below the fingers, and at the same time providing

a depression into which the fingers extend and by which they are protected from contact with the fresh polish applied to surfaces.

While in the foregoing specification I have set forth substantially a single structure in considerable detail for the purpose of illustrating an embodiment of the invention, it will be understood that such details of structure may be varied widely by those skilled in the art without departing from the spirit of my invention.

I claim:

1. A closure adapted for use with a polish container, comprising an upwardly arched diaphragm body providing a cavity and having a spring-urged portion around the mouth of said cavity arranged to engage the outside of the rim of the container to form a seal therewith, a dauber carried by said diaphragm and depending from the lower central portion thereof, said dauber being entirely within said cavity when

said diaphragm is in its upwardly arched position, and means for moving said diaphragm downwardly and past center, whereby said diaphragm occupies a depending position which it will retain until pressed upwardly again by external force past center, said dauber being exposed when said diaphragm is in its depending position.

2. An applicator closure adapted for use with

a polish container, comprising an upwardly arched diaphragm body providing a cavity and having a rim portion around the mouth of said cavity arranged to frictionally engage the outside of the rim of a container to form a seal therewith, a dauber secured to said diaphragm within said cavity, said dauber being entirely within said cavity when said diaphragm is in its upwardly arched position, a handle secured to the upper portion of said diaphragm, said diaphragm, when disengaged from said container, being manipulatable past center to cause it to lie permanently in a depending concave position providing a dish-like shield about said handle with said dauber projecting outwardly beyond said shield, said diaphragm retaining its set, depending position upon the release of pressure thereon.

3. An applicator closure adapted for use with a container filled with solids, comprising an upwardly arched diaphragm body providing a cavity having a rim portion around the mouth of said cavity arranged to engage the peripheral edge of said container for solids, an applicator carried by said diaphragm within said cavity, said diaphragm in one set position substantially enclosing said applicator within said cavity, and said diaphragm being reversible to a set depending position wherein said applicator is disposed outside of said cavity.

HOWARD L. AUTEN.
